UNITED STATES PATENT OFFICE

2,566,388

FLY HOOK HOLDER

John E. Waggoner, South San Francisco, Calif.

Application December 5, 1945, Serial No. 632,847

4 Claims. (Cl. 43--57.5)

1

This invention relates to a fly hook holder and it is one object of the invention to provide a device of this character which is flat and of such dimensions that it may be readily carried in a pocket or placed in a tackle box if so desired.

Another object of the invention is to provide a fly hook holder wherein the flies may be applied to the holder with the fly hooks alternately extending in opposite directions and thus allow a large number of hooks to be mounted in the holder.

Another object of this invention is the provision of spaced transverse strips which serve both as hook engaging means and as seats for anchor blocks which in turn serve as leader engaging means. The edges of these strips furthest from the transverse center of the holder, and herein-after designated as outer edges, are recessed to provide a plurality of pockets for receiving the barbed ends of the hooks and which serve additionally as seats for receiving an elastic band attached to the anchor blocks.

Another object of the invention is to provide a device of this character wherein the members for holding the fly hooks are carried by a sheet having hook-engaging members at opposite sides thereof and mounted in a backing which serves as a protector for the hooks, and in addition provides a device with pockets in which leaders may be placed when not in use.

Another object of the invention is to provide a device of this character which has the blocks carrying the leader-engaging members so mounted that tension or pull may be applied to the leaders and the leaders thus kept straight and also the barbed ends of the hooks firmly held in engagement with the strips at ends of the device.

The invention is illustrated in the accompanying drawings, wherein:

Figure 1 is a perspective view of the fly hook holder.

Figure 2 is a vertical sectional view through the sheet and strips removed from the binder and other portions of the holder and taken substantially on the plane of section line 2--2 of Figure 1.

Figure 3 is a vertical sectional view taken substantially on the plane of section line 3--3 of Figure 1.

Figure 4 is a perspective view of one of the blocks carrying a leader engaging member.

This improved fly hook holder has the appearance of a book and includes in its construction a sheet 1 across end portions of which strips 2 are secured by rivets 3. These strips 2 are in opposed relation to each other at opposite sides of

the sheet and located adjacent opposite ends thereof, and upon referring to Figures 2 and 3, it will be seen that each strip is provided along its outer side edge with a recess 4 so formed that it is divided into a number of pockets 5. Similar recesses 6 are formed along inner side edges of the strip. A binder or backing 7 is provided for the sheet 1 and this backing is formed from leather or other suitable material which may be readily folded without cracking. A shield 8 formed of material not liable to tear easily is provided for the sheet 1 and its strips 2, and this sheet is folded so that the sheet 1 will be disposed between its leaves and shields provided for both sides of the sheet 1. There has also been provided a sheet of tubular material 8' having pockets 9 open along their outer ends for reception of extra leaders. The sheet forming the pockets 9 is disposed flat against the sheet forming the shields 8 and the cover 7 is then applied and openings formed to receive rings 10 which hold the cover, the sheet having the pockets, the shield, and the sheet 1 in assembled relation to each other and allow the portion 7' of the cover to be swung to an open position for removal of leaders from the pockets 9 and also allow the pockets 9 and the shields 8 to be swung away from the sheet 1 to a raised or open position, allowing access to the sheet 1. One of the portions 7' of the backing or cover is of greater width than the other and this wider portion carries a tongue 11 which will hold the cover closed when passed through a strip 12 carried by the narrow portion 7' of the cover.

Fly hooks which are placed in the carrier have the barbed ends of their hooks 13 engaged in the pockets 5 formed along outer side edges of the strips 2. The leaders 14 extend longitudinally of the sheet 1 and are engaged with anchoring members 15 carried by anchor blocks 16. The anchoring members 15 are formed from strands of resilient wire bent so that each anchoring member has a coil 17 from which extend stems 18 and 19. The stems 18 of the anchoring members are embedded in the blocks 16 at their inner ends, that is, the ends closest to the transverse center of the holder, and the blocks are provided with transversely extending openings 20 proximate the opposite or outer ends and longitudinally extending openings 21 extending through said outer ends so that an elastic strand 22 may be readily applied to the blocks and a knot 23 formed to hold the blocks in engagement with the elastic strands. The strands 22 are passed through passages 24 formed in the strips 2 and

the outer end of each elastic strand is provided with a knot 25. It will thus be seen that the elasticity of the strands 22 will normally hold the blocks 16 in the position shown in Figure 2 with their outer end portions seated in the recesses 6 along the inner side edges of the strips 2.

When a fly hook is to be applied to the carrier, the eye at the rear end of the leader 14 of the hook 13 should first be engaged with the anchoring member 15 carried by block 16. To do this, the eye of the leader is passed over the stem 19 and then engaged with the coil 17 of the anchoring member. By pulling on the hook 13, the elastic 22 will be stretched and the barbed end of the hook engaged in the pocket 5 along the outer edge of the strip 2. This can be accomplished with one hand while holding the hook or carrier open with the other hand. If the fly hook should slip from a person's hand, the fly will not be lost from the fly book, as its leader remains in engagement with the anchoring member 15.

To remove the fly hook from the fly carrier, it is merely necessary to pull hook 13 forwardly to release it from the pocket 5 of the strip 2 and then release its leader 14 from the anchoring member 15 by detaching the eye of the leader from the coil 17 and slipping it forwardly above the stem 19.

Each of the strips 2 has been shown formed with twelve of the pockets 5 and such strip carries twelve of the blocks 16, and since the fly hooks are applied in opposite directions longitudinally of the holder with their hooks engaged with one strip 2 and their leaders engaged with the anchoring members carried by blocks of the other strips, twenty-four fly hooks may be applied to the side of the sheet shown in Figure 1. Since strips 2 are mounted at opposite sides of the sheet 1, forty-eight fly hooks may be placed in the carrier with twenty-four at each side of the sheet 1.

While it has been stated that the device is to carry fly hooks, it will be understood that any hook equipped with a leader may be placed in the carrier.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrange-

ment of details coming within the field of invention claimed may be resorted to in actual practice, if desired.

Having thus described the invention, what is claimed is:

1. A fly hook holder comprising a foldable backing, a sheet of strip material swingably mounted on said backing, a plurality of spaced parallel strips transversely carried by said sheet, recess means formed in said strips for frictionally retaining fish hooks, anchor means for detachably retaining leaders associated with the fishhooks, and resilient means for securing said anchor means to said strips, said recess means including a plurality of recesses in the outer and inner side edges of said strips, and a plurality of passages transversely disposed in said strips interconnecting the outer and the inner recesses.

2. The combination of claim 1 wherein said anchor means includes a plurality of blocks abutting said inner recesses and having resilient coils secured to the inner ends thereof for removably retaining leaders.

3. The combination of claim 2 wherein said resilient means includes elastic bands extending through said passages and secured at their extremities to said strips and to the outer ends of said anchor blocks.

4. The combination of claim 3 wherein said anchor blocks include transverse bores proximate the outer ends thereof and longitudinal bores extending through the outer ends thereof, and said elastic bands are knotted at their extremities and retained in said outer recesses and said longitudinal bores.

JOHN E. WAGGONER.
